Fig. 5

*Fig. 6**Fig. 7*

FIG. 1 is a top plan view of a disposable diaper showing my new design; the opposite side of the disposable diaper being substantially the same as the top plan view but different therefrom by the omission of transverse seams;

FIG. 2 is a top plan view of a second embodiment of the diaper shown in FIG. 1; the opposite side of this modified embodiment being identical to the opposite side of the diaper shown in FIG. 1;

FIG. 3 is an enlarged portion of the design as indicated by 3-3 in FIG. 2;

FIG. 4 is a top plan view of a third embodiment of the diaper shown in FIG. 1; it being understood that the pattern uniformly continues over the entire surface of the diaper, and that the opposite side of the diaper is identical to the top plan view;

FIG. 5 is an enlarged portion of the design as indicated by 5-5 in FIG. 4;

FIG. 6 is a top plan view of a fourth embodiment of the diaper shown in FIG. 1, it being understood that the pattern shown uniformly continues over the entire surface of the diaper, and that the opposite side of the diaper is identical to the top plan view of the diaper shown in FIG. 4;

FIG. 7 is an enlarged portion of the design as indicated by 6-6 in FIG. 6.

I claim:

The ornamental design for disposable diapers, as shown and described.
